COMBINATION DRAIN AND PLUG

Arthur C. Wiedoff, Milwaukee, Wis.

Application August 27, 1938, Serial No. 227,119

2 Claims. (Cl. 4—287)

This invention appertains to plumbing, and more particularly to sinks, basins, tubs, and the like.

One of the primary objects of my invention is to provide a novel plug for the waste pipes of wash basins and the like, whereby to effectively prevent the passage of debris into the waste pipe when the plug is unseated to permit the draining of water from the basin into the waste pipe.

10 Another salient object of my invention is to provide means for so constructing the plug that when the same is in its seated position, debris from the overflow will be prevented from going into the drain pipe.

15 A further important object of my invention is to provide a plug for wash basins and the like, having formed thereon or attached thereto a screen, whereby to effectively hold back all foreign matter and prevent such foreign matter from 20 draining into the waste pipe.

25 A further object of my invention is to provide novel means for constructing the plug and strainer whereby the plug and strainer can be readily lowered to a closed position, and also readily raised and held in an open position for permitting the draining of water into the waste pipe.

30 A still further object of my invention is to provide an improved device of the above character, which will be durable and efficient in use, one that will be simple and easy to manufacture, and one which can be placed upon the market at a reasonable cost.

35 With these and other objects in view, the invention consists in the novel construction, arrangement, and formation of parts, as will be herein-after more specifically described, claimed, and illustrated in the accompanying drawing, in which drawing:

40 Figure 1 is a central vertical section through a wash basin equipped with my invention.

45 Figure 2 is a fragmentary sectional view, similar to Figure 1, but showing the plug in lowered position.

Figure 3 is a detailed sectional view, similar to Figure 2, but showing a modified form of my invention, the view being taken on the line 3—3 of Figure 4 looking in the direction of the arrows.

50 Figure 4 is a detailed horizontal section taken on the line 4—4 of Figure 3, looking in the direction of the arrows.

55 Referring to the drawing in detail, wherein similar reference characters designate corresponding parts throughout the several views, the letter B generally indicates a wash bowl, and the letter D a drain or waste pipe therefor. The wash

bowl B and the waste pipe D are of the usual or any preferred character, and the wash bowl B is provided with the usual over-flow passage 5, which leads into the drain pipe D. The drain pipe D leads to the usual trap, and thence to the 5 main outlet.

In accordance with my invention, a flanged, threaded sleeve 6 is placed through the drain opening of the wash basin and is securely fastened thereto by a lock nut 7. The sleeve 6 is connected to the drain or waste pipe D by means of a union nut 8. The flanged upper end of the threaded sleeve 6 fits around the opening in the basin, and forms a valve or plug seat 9. A cross bar 10 is carried by the threaded sleeve 6, and the ends of the cross bar are secured firmly to the threaded sleeve, and, as shown, the bar extends diametrically across the sleeve. The sleeve has an opening 11 formed therein for communication with the over-flow passage 5 of the wash basin. 20

25 My novel drain plug 12 can be formed from brass, or other desired material, and the plug can be plated to enhance the appearance thereof. The plug 12 includes a head or plug body 13, the peripheral edge of which is beveled with snig engagement with the seat 9 in the sleeve 6. The upper edge of the head or body 13 has formed thereon a finger grip 14, whereby the plug can be conveniently raised or lowered. Depending from the body 13 is a cylindrical guide sleeve 15, and this guide sleeve snugly engages the inner surface of the threaded sleeve 6 so that the entire plug 12 can be raised and lowered without tilting movement.

30 The upper end of the cylindrical sleeve 15 has formed therein a plurality of minute openings 16, and hence the sleeve constitutes a strainer. The strainer sleeve 15 can either be formed integral with the head or body 13, or can be formed separately therefrom and be rigidly secured thereto in any known manner. The lower edge of the strainer sleeve 15 has formed therein upwardly extending notches or slots 17. These slots or notches 17 are diametrically opposite one another, and have a width equal to the width of the cross 45 bar 10.

35 In use of my improved strainer and plug, the same is inserted within the threaded sleeve 6, as shown in Figure 1, and the plug and strainer are turned so that the slots or notches 11 will be out of alignment with the cross bar 10, and thus the lower edge of the strainer will rest upon the cross bar 10 and be held in a raised elevated position. All water flowing from the basin into the waste pipe will have to pass through the strainer sleeve, 50 55

and hence all debris, such as hair, hair-pins, and the like, will be retained, and will be prevented from entering into and clogging up the waste pipe. By turning the plug 12 to align the notches or slots 17 with the cross bar 10, the plug can be dropped down so that the beveled edge thereof will rest on the seat 9, and close the basin against outward flow of water. This position is shown in Figure 2, and it is to be noted that the openings in the 10 strainer sleeve cover the opening 11 in the threaded sleeve 6, and hence any water flowing through the over-flow passage-way 5 of the basin will be screened.

Obviously, the entire plug 12 can be quickly removed from the drain pipe for cleaning purposes, and as there is nothing to get out of repair, the plug can be freely manipulated by the ordinary housewife.

In public buildings it may be necessary to take 20 precautions against the removal of the plug 12 from the basins by unscrupulous persons. In Figure 3 I have illustrated one method of accomplishing this purpose. This means can include a depending rod 18. The rod can be threaded into the head or body 13 of the plug 12. The cross bar 10 has formed therein a central opening 19 for slidably receiving the rod 18. The lower end of the rod can have threaded thereon a nut 20, and this nut prevents the removal of the plug from the waste pipe. At a 30 point above the cross bar 10 the rod 18 can have formed thereon or secured thereto an annular rib 21. This rib prevents the dropping of the rod into the waste pipe, should the rod become accidentally detached from the plug 12.

While I have illustrated a wash basin, it is to be understood that my invention is to be utilized in conjunction with wash-tubs, sinks, and the like.

40 My device is exceptionally easy to operate, and, obviously, upon the lifting of the plug the same can be either turned to the right or left, and as soon as the slots 17 ride past the bar 10 the plug will be held against downward movement. While I have shown the openings as being 45 round, it is to be understood that the same can be of any shape, either long, square, or the like.

Changes in details may be made without departing from the spirit or the scope of this invention, but what I claim as new is:

1. The combination with a sink, basin, or the like, having a drain opening, a drain pipe, a 5 flanged, threaded sleeve fitted in the drain opening with the flanged edge disposed around the drain opening, a nut holding the threaded sleeve in position, a union connecting the sleeve with the drain pipe, and a cross bar carried by the 10 sleeve and extending diametrically across the same, of a plug for the sleeve including a solid body having a beveled peripheral edge for fitting against the inner surface of the flanged sleeve, a depending cylindrical member carried 15 by the body and snugly fitted within the sleeve, said member having a plurality of minute perforations therein adjacent to the body, and slots in its lower edge, the slots receiving the cross bar when the plug is in one position for permitting 20 the lower end of the plug of the body to rest on the sleeve and said cross bar holding the plug in elevated position when the lower edge of the plug rests upon the cross bar.

2. The combination with a sink, basin, or the 25 like, having a drain opening, a drain pipe, a flanged, threaded sleeve fitted in the drain opening with the flanged edge disposed around the drain opening, a nut holding the threaded sleeve in position, a union connecting the sleeve with 30 the drain pipe, and a cross bar carried by the sleeve and extending diametrically across the same; of a plug for the sleeve including a solid body having a beveled peripheral edge for fitting against the inner surface of the flanged sleeve, 35 a depending cylindrical member carried by the body and snugly fitted within the sleeve, said member having a plurality of minute perforations therein adjacent to the body, slots in its lower edge, the slots receiving the cross bar when the plug is in one position for permitting the 40 lower end of the plug of the body to rest on the sleeve and said cross bar holding the plug in elevated position when the lower edge of the plug rests upon the cross bar, and means carried by 45 the plug slidable on the cross bar.

ARTHUR C. WIEDOFF.
